DESIGN FOR A FOUNTAIN PEN OR THE LIKE WITH SAFETY GUARD

Tyyne D. Flanagan, Chicago, Ill.

Application December 6, 1945, Serial No. 124,429

Term of patent 3½ years

(Cl. D74—17)

To all whom it may concern:

Be it known that I, Tyyne D. Flanagan, a citizen of the United States, residing at Chicago, in the county of Cook and State of Illinois, have invented a new, original, and ornamental Design for a Fountain Pen or the like with Safety Guard, of which the following is a specification, reference being had to the accompanying drawings, forming part thereof.

The figure is a view in elevation of a fountain pen or the like with a safety guard showing my new design.

I claim:

The ornamental design for a fountain pen or the like with safety guard, substantially as shown.

TYYNE D. FLANAGAN.
